PROPELLER DEICER

Lynn A. Williams, Jr., Northfield, and Henry J. De N. McCollum, Chicago, Ill.; said Williams assignor to Stewart-Warner Corporation, Chicago, Ill., a corporation of Virginia; Thelma McCollum, executrix of said Henry J. De N. McCollum, deceased, assignor to Stewart-Warner Corporation, Chicago, Ill., a corporation of Virginia

Application March 20, 1943, Serial No. 479,896

12 Claims. (Cl. 244—134)

1

Our invention relates to propeller de-icers and more particularly to a propeller de-icer wherein internal combustion heaters are located in the hollow blades of an airplane propeller.

In airplane operation, considerable difficulty is experienced with the formation of ice on the propeller blades under certain conditions of atmospheric temperature and humidity. Attempts have been made in the past to eliminate the formation of this ice by discharging of the engine exhaust gases through passages in the propeller blades with a view to heating these blades sufficiently to prevent the formation of ice thereon. Such arrangements have numerous disadvantages and have proved unsatisfactory.

Attempts have also been made to solve the de-icing problem by installing electric heaters in the propeller blades. Such heaters are heavy and consume greater quantities of current than are readily available, so that a special generator must be installed to furnish the current for such heaters. The addition of this special generator materially increases the weight of the installation and results in a substantial reduction in the power output of the airplane engine where this generator is driven by such engine. Where a special engine is provided to drive the generator, the weight of the installation is still further increased.

An object of our invention is to provide a new and improved propeller de-icer which will supply the desired quantity of heat and which can readily be rendered inoperative when heat for de-icing is not required.

Another object of our invention is to provide a new and improved de-icer wherein internal combustion heaters are located in the shanks of hollow propeller blades and are supplied with fuel by a barometric control which meters the fuel to furnish the correct amount for constant propeller speed at any altitude.

Another object of our invention is to provide a propeller de-icer which may be readily installed in an adjustable pitch propeller of the types now in service.

Another object of our invention is to provide a new and improved propeller de-icer which requires only a small amount of electrical current for its operation.

Another object of our invention is to provide a new and improved propeller de-icer which may be supplied with fuel from the main fuel tank or tanks of the aircraft or may have its own separate source of fuel supply as desired.

Another object of our invention is to provide

2 a new and improved propeller de-icer which is sturdy, reliable, efficient, and inexpensive to manufacture and install.

Another object of our invention is to provide 5 a new and improved propeller de-icer which requires a minimum of attention on the part of the operator of the aircraft.

Other objects and advantages will become apparent as the description proceeds.

10 In the drawings:

Fig. 1 is an irregular, sectional view showing 15 our invention applied to a controllable pitch propeller. This view is taken generally on the line 1—1 of Fig. 3;

Fig. 2 is a transverse, sectional view through 20 one of the propeller blades and is taken on the line 2—2 of Fig. 1;

Fig. 3 is an irregular, sectional view taken generally on the line 3—3 of Fig. 1; and

25 Fig. 4 is a view showing a partial, longitudinal section through a propeller blade. This view is on an enlarged scale and is taken on the line 4—4 of Fig. 2.

In the drawings, we have shown our invention 30 as being applied to a typical adjustable pitch propeller of the automatic type wherein weights or other suitable devices are utilized to shift the propeller blades to afford a substantially uniform propeller speed for all conditions of operation.

In general, this adjustable pitch propeller is 35 illustrated as comprising three hollow blades 19, each having a root or base end 12 rotatably mounted in a bearing 14 carried in one of the arms 16 of a hub 18. As best shown in Fig. 3,

the hub 18 is attached by bolts 29 to the flange 40 22 of a sleeve 24 having longitudinally extending splines 26 located in longitudinal grooves 28 formed in the crank shaft 30 or an extension attached thereto and rotatable therewith. Each

45 of the propeller blades is rotatable for pitch adjustment in its bearing by a ring gear 32 which meshes with a common bevel gear 34 driven by the pivoted weights or other automatic adjusting means. The propeller mechanism thus far described is no part of our invention and has

50 merely been selected as typical of adjustable pitch propeller mechanisms. In some instances, the blades of an adjustable pitch propeller are shifted to vary their pitch by an electric motor, hydraulic motor, or other suitable manually or automatically controlled mechanisms and our invention is intended to be used with all types of variable pitch propellers.

An internal combustion heater 36 is located in 55 the base of each propeller blade adjacent the

root end 12 thereof. Each heater 36 comprises a combustion chamber 38 having a cylindrical wall 40 and an end wall 42. Combustible mixture is supplied to that portion of the combustion chamber adjacent the end wall 42 by an induction tube 44 having a curved end 46 located in the combustion chamber and serving to preheat the mixture supplied thereto. The induction tube 44 is preferably of uniform diameter and discharges the combustible mixture in such manner as to create a ring of flame in the combustion chamber.

A housing 48 is attached to the cylindrical wall 40 of the combustion chamber and provides a passage 50 in which a plug type of electric igniter 52 is located. The igniter 52 is of smaller diameter than the passage 50, so that an annular space is provided around the igniter for passage of combustible mixture therewith. Part of the combustible mixture delivered by the induction tube 44 flows through an inlet 54 into the lower end of passage 50 and is heated as it passes between the igniter 52 and the wall of the passage 50. This mixture is ignited by the hot wire 55 located in the end of the igniter and the burning mixture passes from the passage 50 through outlet 56 into section 58 of the combustion chamber which is located between rings 60 and 62.

The ring 60 has an inwardly projecting portion 64 which is directed toward the wall 42 of the combustion chamber and tends to prevent liquid fuel from escaping from that portion of the combustion chamber which contains the end 46 of the induction tube except by passing into the passage 50, where it is vaporized by the igniter 52. The ring 62 tends to prevent the escape of any liquid fuel from the portion 58 of the combustion chamber and the combination of these rings effectively insures complete combustion of all liquid fuel before this fuel can pass out of the combustion chamber.

Certain features pertaining to the construction and arrangement of the combustion chamber, induction tube and igniter are the sole invention of Henry J. De N. McCollum and are claimed in his co-pending applications, Serial No. 477,080, filed February 25, 1943, and Serial No. 478,258, filed March 16, 1943.

Each induction tube 44 extends through a wall of a propeller blade and has an inlet end attached to a Venturi tube 66. Each Venturi tube has a restricted throat into which fuel is discharged by a fuel jet 68 connected by a flexible hose 70 to a nipple 72 attached to a slinger ring 74. The tube 66 and jet 68 constitute a carburetor supplying a combustible mixture to the combustion chamber. The slinger ring is V-shaped in cross-section and rotates with the propeller hub 18. The flexible hoses 70 permit the individual propeller blades to be rotated relative to the hub 18 for pitch adjusting purposes without disturbing the supply of fuel from the slinger ring 74 to the burners located in these blades.

Fuel is supplied to the slinger ring 74 by a stationary pipe 76 supported in a bracket 78 attached to any suitable part of the airplane engine or fuselage. The pipe 76 has a curved end 80 forming a spout located in the groove of the slinger ring 74 and delivering fuel to this ring as the latter rotates with the propeller blades. A second pipe 82 leads from an engine fuel tank or a separate fuel tank for the de-icer, as may be preferred, and is connected to the pipe 76 by way of a solenoid control shut-off valve 84 and an altitude compensator 86 which varies the rate

of flow of fuel to the slinger ring in accordance with variations in atmospheric density. Such altitude compensators are well-known and any suitable type may be used. The solenoid valve 84 is opened by closing a switch 88 in a circuit connecting this valve with a suitable source of electrical energy, such, for example, as a battery 90.

The fuel delivered to each Venturi tube 66 by its associated jet 68 mixes with air entering the inlet or lefthand end of the Venturi tube to form a mixture of fuel and air which is delivered to a combustion chamber 42 through an induction tube 44. The inlet of each Venturi tube 66 is exposed to the pressure existing in the spinner 92. This spinner serves to protect the inlets of the Venturi tubes against dirt and moisture, but the interior of this spinner is in open communication with atmosphere and the pressure in this spinner varies with variations in atmospheric pressure.

The mixture of fuel and air supplied to each combustion chamber burns therein and is discharged into the interior of one of the hollow propeller blades 10 where it mixes with secondary air drawn into the interior of the blade through openings 94 located opposite the base of the combustion chamber and serving to connect the interior of this blade with the interior of the spinner 92. This secondary air mixes with the hot products of combustion issuing from the combustion chamber and somewhat reduces the temperature of these products of combustion. The resulting admixture of products of combustion and secondary air then flows radially outward of the blades under the influence of centrifugal force and is discharged to atmosphere through a suitable outlet of openings 96 adjacent the tip of the blade.

From the foregoing, it will be apparent that the action of centrifugal force on the products of combustion and secondary air is relied upon to move these fluids from the roots to the tips of the propeller blades. The same centrifugal force which causes this flow of gases toward the tips of the propeller blades also serves to draw combustible mixture into the combustion chambers and secondary air into the place through the openings 94. Centrifugal force acting on the fuel in the flexible hoses 70 feeds this fuel toward the Venturi tubes 66 and jet 68 and the nipples 72 are preferably provided with restrictions 98 to insure even distribution of the fuel among the several burners and uniform rates of flow to these burners.

Each burner has a sufficient heat output to melt any snow and ice which may collect on its propeller blade and to maintain this blade throughout its entire surface area at a temperature above freezing throughout the atmospheric temperature range which is favorable to the formation of ice and snow on the propeller blades. When the atmospheric temperature is above freezing, no heat, of course, is required and the switch 88 may then be opened to shut off the supply of fuel to the burners. Likewise, when the atmospheric temperature is well below freezing and all moisture in the air is frozen in the form of snow or ice, there is no need to heat the propeller blades and the control switch 88 should be in the open or off position. Our novel propeller de-icer is only needed when atmospheric temperature and humidity conditions are such that snow and ice tend to accumulate on the propeller blades and the solenoid valve 84 controlled by the

manual switch 88 provides a ready means for starting and stopping the operation of our propeller de-icer.

The exhaust outlets at the tips of the propeller blades are preferably located at the extreme end, as is the outlet indicated by reference character 96. However, these outlets may, if desired, be located a short distance from the extreme end of the propeller blade, as is the outlet 96'. This latter outlet is so positioned that the suction created by a propeller blade as it moves through the air also tends to create a circulation through the propeller blade. Since the pull of centrifugal force is sufficient to provide the requisite flow through the hollow propeller blade, the additional pull of suction is not required and the position of the outlet 96' has the slight disadvantage that a partially dead space is formed in the extreme tip of the propeller blade where condensed moisture may collect. Either arrangement of the exhaust outlets, however, will provide satisfactory operation.

In the particular embodiment shown in the drawings, the igniters 52 are supplied from the same battery which furnishes the current for opening the solenoid fuel valve 84. Each igniter 52 has a wire 100 leading to a two part metal sleeve 102 which rotates with the propeller hub 18. This two part sleeve is mounted on an insulating ring 104 interposed between the sleeve 102 and a supporting sleeve 106 attached to the hub 18 by bolts 20. Electricity is conducted to the sleeve 102 by a carbon contact 108 resiliently mounted in a stationary housing 110 supported in a bracket 111 attached to the forward end of the engine or any suitable part of the airplane fuselage. A conductor 112 connects the brush to a push button switch 114, which in turn is connected to the battery 90 by wire 116.

In order to prevent any sparks formed at the contact 108 from igniting fuel in the slinger ring 74, we preferably provide a two part ring 102 with a radially extending flange 118 which forms a shield between the contact 108 and the slinger ring. It is understood that the wires 100 connecting the igniters with the ring 102 are sufficiently flexible to permit the individual propeller blades to be rotated in the hub 18 to change the pitch of these blades without disturbing the electrical connections to the igniters.

Whenever it is desired to start the propeller de-icer, the pilot or a member of the airplane crew closes the switch 88 and presses down on the push button 114. When switch 88 is closed, solenoid valve 84 opens and permits fuel to flow to the jets 68. As the fuel is discharged from these jets, it mixes with air entering the Venturi tube 66 and forms a fuel and air mixture delivered to the combustion chambers by way of induction tubes 44. As soon as the pilot has closed the switch 88, he presses down on the push button 114, thereby closing the circuits to the several igniters 52. In a few seconds, the hot wires 54 of these wires reach ignition temperature. Part of the fuel and air mixture delivered to the combustion chambers enters the passages 50 surrounding the igniters 52 and is ignited by the hot wires of these igniters. The resulting combustion ignites all of the combustible mixture being supplied to the combustion chambers by the induction tubes 44 and as soon as this occurs a ring of flame is created in the base of each combustion chamber which suffices to maintain combustion therein. The push button 114 may then be released to disconnect the igniters from their source of current.

When the induction tubes 44 are cold, some of the fuel entering the combustion chambers may still be in liquid form. The rings 60 prevent this fuel from passing from the combustion chambers directly into the blades 10 and deflect this liquid fuel into the passages 50 surrounding the igniters 52. The heat of these igniters vaporizes this liquid fuel and forms a rich mixture which may be readily set on fire by the hot wires 55. If the push button switch 114 is not closed immediately after the switch 88 is closed, the igniters 52 remain cold and liquid fuel entering the passages 50 may flow upwardly along the walls of these passages and into the upper parts of the combustion chambers. Under these conditions, the rings 62 will prevent the escape of this fuel from the combustion chambers into the interior of the propeller blades.

The rings 60 and 62 also serve to retard somewhat the outward flow of gases from the combustion chambers and thus promote complete combustion of the gases prior to discharge of these gases from the outlet ends of the combustion chambers.

The gases discharge from the combustion chambers and mix with secondary air admitted through the openings 94 in the bases of the propeller blades and the admixture thus formed then flows lengthwise of these blades. This admixture is hottest adjacent the discharge ends of the combustion chambers and gradually cools as it travels lengthwise of the propeller blades. However, the rate of transfer between these gases and the walls of the propeller blades varies with the rates of flow of these gases, being greatest where the rates of flow are greatest. The cross-sectional areas of the hollow interiors of the propeller blades decrease from a maximum adjacent the roots of these blades to a minimum adjacent the tips of these blades, so that the rate of heat transfer from the gases to the blades tends to increase as the gases approaches the tubes due to the greater rate of flow of these gases.

Our new and improved propeller de-icer is particularly adapted for de-icing airplane propellers of the adjustable pitch type, but it is also equally useful in de-icing fixed types of airplane propellers and also propellers used for driving sleds or for any other purposes where the propeller is exposed to temperature and humidity conditions which favor the accumulation of ice or snow on the propeller blades.

While we have shown and described only a single embodiment of our invention, it is to be understood that our invention is not limited to the details shown and described, but may assume numerous other forms and that the scope of our invention is defined by the following claims.

We claim:

- 60 1. A propeller de-icer, comprising a propeller having a hollow blade, a combustion chamber rotatable with said propeller and supplying hot products of combustion to the interior of said blade, a stationary source of fuel for said combustion chamber, a rotating U-shaped ring movable with said propeller, a connection for conducting fuel from said source to said ring, a carburetor for said combustion chamber, a connection between said ring and said carburetor, and means for igniting combustible mixture supplied to said combustion chamber by said carburetor.
- 65 2. De-icing means for a hollow propeller blade, comprising a cup-shaped combustion chamber having a base located near the hub end of said blade and an open end directed toward the tip of
- 70
- 75

said blade, an induction tube extending through a wall of said blade, a carburetor connected to the outer end of said induction tube, means for supplying fuel to said carburetor, a housing attached to a side wall of said combustion chamber and having a passage connected at opposite ends to said combustion chamber, an electrical igniter located in said housing, a ring for deflecting liquid fuel from said combustion chamber into said passage, and a second ring for preventing liquid fuel leaving said passage from passing out of said combustion chamber.

3. Apparatus of the class described, comprising a propeller having a plurality of hollow blades rotatable about the axis of a common drive shaft, an internal combustion heater for each of said blades, an electrical igniter attached to each of said heaters, a carburetor for each of said heaters, said heaters, carburetors and igniters being rotatable about said axis, a non-rotatable source of fuel for said carburetors, a slinger ring rotatable with said blades about said axis, a connection between each carburetor and said ring, a non-rotatable nozzle for supplying fuel to said slinger ring, altitude responsive means for varying the rate of fuel flow to said slinger ring, a solenoid valve for cutting off the flow of fuel to said ring, a manual switch for controlling said valve, a non-rotatable source of current for said igniters, a rotating ring electrically connected to all igniters, a stationary brush contacting said ring and connected to a source of current, and a push button controlling electrical connection between said brush and said source.

4. Apparatus of the class described, comprising a propeller having a plurality of hollow blades rotatable about the axis of a common drive shaft, an internal combustion heater for each of said blades, an electrical igniter for each of said heaters, a carburetor for each of said heaters, said heaters, carburetors and igniters being rotatable about said axis, a non-rotatable source of fuel for said carburetors, connections between said carburetors and said source, a solenoid valve for cutting off the flow of fuel to said carburetor, a manual switch for controlling said valve, a non-rotatable source of current for said igniters, a rotating ring electrically connected to all igniters, a stationary brush contacting said ring and connected to a source of current, and a switch controlling electrical connection between said brush and said source.

5. Apparatus of the class described, comprising a propeller having a plurality of hollow blades rotatable about the axis of a common drive shaft, an internal combustion heater for each of said blades, an electrical igniter for each of said heaters, a carburetor for each of said heaters, said heaters, carburetors and igniters being rotatable about said axis, a non-rotatable source of fuel for said carburetors, a slinger ring rotatable with said blades about said axis, a connection between each carburetor and said ring, a solenoid valve for cutting off the flow of fuel to said ring, a manual switch for controlling said valve, a non-rotatable source of current for said igniters, a rotating ring electrically connected to all igniters, a stationary brush contacting said ring and connected to a source of current, and a push button controlling electrical connection between said brush and said source.

6. Apparatus of the class described, comprising a propeller having a hollow blade rotatable about the axis of a drive shaft, an internal combustion

heater for said blade, an electrical igniter for said heater, a carburetor for said heater, said heater, carburetor and igniter being rotatable about said axis, a non-rotatable source of fuel for said carburetor, a slinger ring rotatable with said blade about said axis, a connection between each carburetor and said ring, a non-rotatable nozzle for supplying fuel to said slinger ring, a solenoid valve for cutting off the flow of fuel to said ring, a manual switch for controlling said valve, a non-rotatable source of current for said igniter, a rotating ring electrically connected to said igniter, a stationary brush contacting said ring and connected to a source of current, and manual means controlling electrical connection between said brush and said source.

7. De-icing means for a hollow propeller blade, comprising a cup-shaped combustion chamber having a base located near the hub end of said blade and an open end directed toward the tip of said blade, an induction tube extending through a wall of said blade, a carburetor connected to the outer end of said induction tube, means for supplying fuel to said carburetor, a housing attached to a side wall of said combustion chamber and having a passage connected at opposite ends to said combustion chamber, an electrical igniter located in said housing, and a ring for deflecting liquid fuel from said combustion chamber into said passage.

8. Apparatus for de-icing a hollow blade propeller, including in combination, a combustion chamber mounted within and rotatable with said propeller and supplying hot products of combustion to the interior of said blade, a Venturi tube secured to the blade having an inlet opening communicating with atmosphere and an outlet opening within said combustion chamber, and means including a conduit rotating with the blade having an outlet opening for supplying fuel to Venturi tube and air inlet, an annular passage rotatable with the propeller connected to said inlet, and a fixed conduit associated with said annular passage for supplying fuel to the combustion chamber.

9. De-icing apparatus for a hollow propeller blade, including in combination, a cup-shaped combustion chamber having a base located near the hub end of said blade and an open end directed toward the tip of said blade, means for supplying carbureted fuel to the interior of said combustion chamber and near its base, means including an igniter and a conduit in which said igniter is located communicating with said combustion chamber near its closed and open ends, and a ring secured inside said combustion chamber between the ends of said igniter containing conduit for deflecting liquid fuel from said combustion chamber into said conduit.

10. Apparatus for de-icing a hollow blade propeller, including in combination, a cup-shaped combustion chamber mounted within the propeller blade and having a base located near the hub end of said blade and an open end directed toward the tip of said blade, means including an induction tube discharging into said chamber adjacent the base of said cup for supplying fuel to said chamber, a pair of fuel deflector rings located between said base and the open end of said cup, each of said rings having inwardly projecting inclined flanges for preventing escape of liquid fuel from said combustion chamber, a by-pass passage located around the ring nearest the base, and an igniter located in said by-pass passage.

11. Apparatus for de-icing a hollow blade propeller, including in combination, a combustion chamber rotatable with said propeller and supplying hot products of combustion to the interior of the blade, means including a stationary fuel jet and an annular inwardly opening ring facing the jet and rotatable with the propeller for supplying fuel to the ring, a carburetor rotatable with the combustion chamber, and a fuel connection between said ring and said carburetor for supplying fuel from said ring to said carburetor.

12. An internal combustion heater, comprising a cup-shaped combustion chamber through which liquid fuel tends to escape, a secondary air chamber surrounding said combustion chamber into which the products of combustion from the open end of said cup-shaped chamber flow, an induction tube for supplying combustible mixture to said combustion chamber, said induction tube discharging into said combustion chamber adjacent the base of said cup, a pair of spaced apart rings located between said base and the open end of said cup, each of said rings having inwardly projecting inclined flanges for preventing escape of liquid fuel from said combustion chamber, a

25

by-pass passage around one of said rings, and an igniter located in said by-pass passage.
